United States Patent Office.

ALFRED D. TATE, OF PEEKSKILL, NEW YORK.

Letters Patent No. 86,328, dated January 26, 1869.

IMPROVED MOP-WRINGER.

The Schedule referred to in these Letters Patent and making part of the same.

To all whom it may concern:

Be it known that I, ALFRED D. TATE, of Peekskill, in the county of Westchester, and State of New York, have invented a new and useful Improvement on a Machine or Contrivance for Wringing Mops; and I do hereby declare that the following is a full, clear, and exact description of the construction and operation of the same, reference being had to the annexed drawings, making a part of this specification, in which—

Figure 1 represents the contrivance or device when attached to a common pail or bucket, and closed, and Figure 2 represents the same unattached and open. The standard A is secured to the bottom of the bucket by means of screws or bolts.

To the long post B, of the standard A, is riveted, at c, the bracket C, in which moves the roller D.

To the short post E, of the standard A, is hinged, at f, the bracket F, in which moves the roller G, and which is thrown backward and forward by means of the lever h thrust in the socket H.

The projections I I, on the bracket C, are designed to close the space at the ends of the rollers, to prevent the mop running off at the ends of the rollers.

Fig. 2 shows the position of the rollers when the

lever is thrown back. The lever resting on the edge of the bucket, brings the bracket F perpendicular and in line with the post E, leaving sufficient space between the rollers for washing the mop.

In order to dry the mop, it is placed against the roller D, the edges being kept within the projections I I. The roller G is thrown forward by raising the lever h.

In applying pressure, the foot is placed on the foot-piece K, which is attached to lower part of the bucket, on the outside, and the knee is pressed against the lever. The mop is then drawn upward, coming from the rollers as dry as can be made by wringing with the hands, and by far less exertion.

What I claim as my invention, and desire to secure by Letters Patent, is—

The combination and arrangement of the standard A, posts B and E, with the rollers G D, lever H, and bracket F, in the manner and for the purpose herein set forth.

ALFRED D. TATE.
